CORE DRILL

Filed March 21, 1923

Fig. 1.

UNITED STATES PATENT OFFICE.

RALPH WILCOX, OF CHICAGO, ILLINOIS, ASSIGNOR TO SULLIVAN MACHINERY COMPANY, A CORPORATION OF MASSACHUSETTS.

CORE DRILL.

Application filed March 21, 1923. Serial No. 626,447.

My invention relates to core drills.

It has for its object to provide an improved core barrel. A further object is to provide such a core barrel having improved core holding means whereby the core may be retained in the core barrel during removal of the latter from the hole. A still further object of my invention is to provide an improved core barrel having improved fluid passage means whereby the same is especially adapted to use with mud fluid. A more specific object of my invention is to provide an improved core barrel especially adapted to use with mud fluid and to handle large cores, for example, such as those made in oil well drilling, whereby the use of mud fluid is facilitated and whereby despite the weight of the core or despite the variation in diameter of the core which frequently occurs in soft formations, which ordinarily would result in the core slipping down through the core lifter, the core is effectually held in the core barrel in such manner as to eliminate the necessity for fishing the same out from the bottom of the hole in an extra and time consuming operation after the elevation of the barrel. These and other advantages of my improved construction will, however, hereinafter more fully appear.

In the accompanying drawings I have shown two embodiments which my invention may assume in practice.

In these drawings,

Fig. 1 is a vertical sectional view of a portion of a core barrel equipped with my improvement.

Fig. 2 is a transverse sectional view on line 2—2 of Fig. 1.

Fig. 3 is a detail sectional view in general similar to Fig. 1 and showing a modified construction.

In this illustrative construction I have shown an improved core barrel of the Mitchell type, generally indicated at 1, and comprising an internally and externally longitudinally fluted diamond carrying bit 2 threaded into a tapered shell and core lifter section 3 of reduced external diameter and carrying a usual core lifter, herein in the form of a resilient split ring 4, this section 3 in turn being threaded onto an externally longitudinally fluted section 5 of the core barrel which is herein of improved construc-

tion and associated with improved core holding means hereinafter described.

More particularly referring to Fig. 1, it will be noted that the lower end 6 of the fluted section 5 which extends into the section 3 is bored concentrically with the bit and of substantially the same internal diameter as the bit and likewise provided with fluid passages therein, herein in the form of longitudinal flutes 7, corresponding to the flutes in the inner periphery of the bit. Above this end portion 6, however, it will be noted that the section 5 is eccentrically bored as at 8 to provide a larger passage, whose circumference is at one point coincident with that of the bore in the portion 6 in such manner as to provide a proper core passage. As shown, this passage 8 is also provided with fluid passages or longitudinally extending flutes 9 therein, certain of which form extensions of the flutes 7 in the end portion 6. By reason of the eccentric boring, it will be noted that a shoulder or ledge 10 is thus provided at the upper end of the end portion 6 which, as herein, preferably extends a substantial distance around the same, herein over half-way around the same. In my present construction, as preferably, I also provide a second and like eccentric bore 11 in the section 5 above the bore 8 and communicating therewith, which in turn produces a second shoulder or ledge 12, similar to the shoulder or ledge 10 but preferably differently located radially with respect to the ledge 10 and herein oppositely disposed with respect thereto. It will moreover be evident that if desired more than two eccentric bores may be provided, depending upon the particular conditions existing.

In the operation of my improved construction, where core conditions are favorable the core will be fed up through the barrel in the usual manner through the usual core passage which is provided coincident with the inner periphery of the bit, the split ring core lifter 4 in its usual manner gripping and holding the core when it is broken off from the bottom of the hole. In a usual construction, however, should the core for any reason, as for example a variation in diameter of the core such as is encountered in soft formations, slip through

the core lifter, the core would be left in the hole and require considerable time to be lost in fishing it out. The same difficulty has been encountered with heavy cores and cores 5 of the size necessary in oil well drilling which run from four to six inches in diameter and consequently have such great weight that the core may be forced through the friction grip of a usual core lifter. As a 10 result of my improved construction including the eccentric bore 8 or bores 8 and 11 and the shoulder or ledge 10 or shoulders or ledges 10 and 12, it will be noted that when for any reason the core slips through 15 the core lifter, a portion of the core brings up against the shoulder or ledge 10, or where, as preferably, a plurality of shoulders or ledges is provided, against one or the other of the shoulders or ledges in such 20 manner as to arrest its movement and prevent loss of the core. More particularly it will be noted that due to the arrangement of the ledges on opposite sides of the path of the core, what may be called "baffle" 25 means are provided for catching the latter on one side or the other, in such manner as to enable the core to be lifted and thus effectively overcome the difficulties heretofore experienced. Here attention is also directed to the fact that by the internal longitudinal flutes in the end portion 6 of the section 5, it is made possible for mud fluid, or water, but more particularly mud fluid, to pass freely up through the core barrel 30 around the core in the desired manner, the internal flutes providing ample clearance therefor. Moreover, through extending certain of the flutes through the larger eccentric bore 8, it will also be observed that ample clearance is provided through the 35 length of the section 5.

In Fig. 3 I have illustrated a modified construction which, while not preferred or ordinarily necessary, may be used if desired, either alone or in conjunction with one or more shoulders or ledges further up in the core barrel. In this construction it will be observed that an eccentric portion 13 is provided in the bit 2 below the core lifter 40 and adapted to function in essentially the same manner as the construction previously described, it being evident that if desired the bit may be lengthened as necessary to provide the core with the requisite access to the eccentrically disposed ledge or shoulder 14.

As a result of my improvement, it will be observed that an effective core holding means is provided whereby through the core 45 being caught by a shoulder or ledge or a plurality of the same, the weight is effectively removed from the split ring core lifter in such manner as to enable the latter to grip and hold its then shorter and lighter section of core even if it is slightly

smaller than the usual diameter, and thereby enable the entire core under average circumstances to be lifted from the hole irrespective of its weight or variations in diameter, all in such manner as to enable 70 larger cores to be removed than it has heretofore been thought possible to remove and accordingly to enable the field of use of core drills to be expanded, this expansion being especially marked in the oil well drilling 75 field. It should, however, be understood that my invention is not limited to use in connection with large cores or to use in the oil well drilling field, it instead being obvious that the same may be used irrespective 80 of the size of the core or the type of drilling wherever for any reason the ordinary core lifter forms an ineffective core holding means. These and other advantages of my improved construction will, however, be 85 clearly apparent to those skilled in the art.

While I have in this application specifically shown and described two forms which my invention may assume in practice, it will be understood that these forms are 90 shown for purposes of illustration and that the invention may be modified and embodied in various other forms without departing from its spirit or the scope of the appended claims.

What I claim as new and desire to secure by Letters Patent is:

1. A core barrel having a core receiving passage, and oppositely disposed eccentrically formed stationary core holding means 100 spaced longitudinally of the barrel adjacent the core passage.
2. A core barrel having a core receiving passage, and oppositely disposed eccentrically formed core holding means spaced 105 longitudinally of the barrel and disposed outside of the core passage.
3. A core barrel having core lifting means and a central core passage, and a plurality of supplemental core holding means rotatable with the barrel and disposed in longitudinally spaced staggered relation outside of said core passage.
4. A core barrel having a core receiving passage, core lifting means, and supplemental core holding means comprising a plurality of oppositely disposed core engaging ledges spaced longitudinally of the barrel and formed outside of said passage.
5. A core barrel having core lifting means 115 and a central core passage, and supplemental core holding means comprising a plurality of ledges disposed in staggered relation outside of said core passage.
6. A core barrel having a core lifting 120 means and a central core passage, and supplemental core holding means disposed in staggered relation outside of said core passage and operative upon failure of said lifting means to positively engage the core.

7. A core barrel having a core receiving passage of substantially the same diameter throughout its length, core lifting means, and supplemental oppositely disposed stationary core holding means formed outside of said passage intermediate its ends at points spaced longitudinally of the barrel. 50
- 5 8. A core barrel having a core receiving passage, core lifting means, and supplemental oppositely disposed stationary baffle means spaced longitudinally of the barrel and formed outside of said passage and engageable by a core when slipping through said lifting means. 55
- 10 9. A core barrel having core lifting means, and supplemental oppositely disposed eccentrically formed stationary core holding means spaced longitudinally of the barrel and engageable by the core upon failure of 60 said lifting means.
- 15 10. A core barrel having core lifting means, a core receiving passage, and means rotatable relatively to said lifting means and formed outside and at opposite sides of 65 said passage intermediate its ends at points spaced longitudinally of the barrel and automatically operative to reduce the weight of the core on said lifting means.
- 20 11. A core barrel having core lifting means and a central core passage, and a pair of longitudinally spaced core engaging shoulders oppositely disposed with respect to the core passage and formed wholly outside the latter. 70
- 25 12. A core barrel having core lifting means, and a plurality of passages above the core lifting means eccentric to the core passage and larger than the latter said passages terminating at their lower ends at 75 points spaced longitudinally of the barrel and presenting core engaging shoulders on opposite sides thereof. 80
- 30 13. A core barrel comprising a bit, a core lifter, and means above the latter presenting a core passage of substantially the same internal diameter as the bit and communicating eccentrically and oppositely located 85
- 35 larger passages presenting core engaging shoulders at points spaced longitudinally of the barrel. 50
- 40 14. A core barrel comprising a bit, a core lifter, and means above the latter presenting a core passage of substantially the same internal diameter as the bit and communicating eccentrically and oppositely located 90
- 45 larger passages presenting core engaging shoulders at points spaced longitudinally of the barrel and having fluid passages in the walls of both passages. 55
- 50 15. A core barrel element disposable in a core barrel at a point above the bit and including an external portion having liquid conducting passages therein and an internal core passage likewise having liquid conducting passages therein and including communicating eccentrically and oppositely disposed passages of greater diameter presenting core engaging abutments at points spaced longitudinally of the barrel. 60
- 55 16. A core barrel, a resilient core lifter 70 ring normally disposed coaxial therewith and having a conical seat therein, an internally and externally fluted bit carried thereon below said core lifter, and means cooperating with the bore through said bit 75 and said lifter and forming a core passage disposed above said lifter and likewise having internal flutes therein, said last mentioned means likewise having therein oppositely disposed bores eccentric with respect 80 to the core passage and forming a part thereof, said bores forming core engaging shoulders at their lower ends at points spaced longitudinally of the barrel. 85
- 60 17. A core cutting bit and a central core barrel having a core receiving passage extending therethrough, and stationary core holding means including a bore disposed eccentrically of said core passage and outside thereof, said bore presenting a core engaging ledge adjacent said core passage. 90
- 65 In testimony whereof I affix my signature.
- 70 RALPH WILCOX.
